[57] CLAIM

The ornamental design for an integral level and handle for shank-type tool, as shown and described.

DESCRIPTION

FIG. 1 is a perspective view of the integral level and handle for a shank-type tool showing my new design;

FIG. 2 is a reduced top plan view thereof;

FIG. 3 is a reduced side elevational view thereof, the opposite side being a mirror image;

FIG. 4 is a reduced bottom plan view thereof showing a tool-bit in broken lines for illustrative purposes only;

FIG. 5 is a reduced left end elevational view thereof;

FIG. 6 is a reduced right end elevational view thereof.

FIG. 1

FIG. 6

FIG. 5

FIG. 4

FIG. 2

FIG. 3
